UNITED STATES PATENT OFFICE.

CHARLES F. PYM, OF ESSEX, ONTARIO, CANADA, ASSIGNOR TO KRENTLER-ARNOLD HINGE LAST COMPANY, OF DETROIT, MICHIGAN, A CORPORATION OF MICHIGAN.

HINGED LAST.

No. 888,261.

Specification of Letters Patent.

Patented May 19, 1908.

Application filed August 2, 1907. Serial No. 386,731.

To all whom it may concern:

Be it known that I, CHARLES F. PYM, a subject of the King of Great Britain, and resident of Essex, in the county of Essex and Province 5 of Ontario, Canada, have invented an Improvement in Hinged Lasts, of which the following description, in connection with the accompanying drawings, is a specification, like letters on the drawings representing like 10 parts.

My present invention aims to secure great rigidity and strength, and at the same time simplicity of construction and operation, in a boot and shoe last. The hinged last has long 15 been recognized as the most desirable form of last, but, in view of the fact that the hinging of the heel-part and forepart must necessarily be effected at the waist or middle of the last, which is the very part of the last 20 which should be left as strong as possible, and which should not be weakened by cutting away the wood or introducing a hinge, pivot pins, etc., the problem of making a practical commercial hinged last capable of enduring 25 the rough usage and great strain brought upon a last in a shoe factory, has proved exceedingly difficult. The result has been that as a rule those lasts which have been simple in construction have been lacking in strength, 30 and those lasts which have been sufficiently strong have been complex or unduly expensive. Accordingly, I have succeeded in devising a construction at once simple and exceedingly strong, in which I employ a relatively broad vertical hinge-plate occupying a 35 narrow kerf or slot in the forepart and a similar slot in the heel-part for a sufficient vertical distance to resist effectively all wrenching and twisting strains, and I provide overlapping approximately horizontal shoulders 40 extending entirely across the abutting walls of the forepart and heel-part at the horizontal middle or largest horizontal diameter of the waist, thereby affording the greatest overlapping contact of the wood of the forepart 45 and the wood of the heel-part when the last is bottom up as required in actual shoe shop use. This enables me to place the pivot of the hinge low down in the forepart so as to 50 secure a quick-shortening swinging movement without introducing any substantial weakness into the last, because, in my construction, the hinge is not required to sustain the vertical pressures as heretofore in this 55 type of last, but these are mainly borne di-

rectly by the wood at the bulge or widest portion of the waist of the last as explained.

In the drawings, in which I have shown a preferred embodiment of my invention, Figures 1 and 2 are fragmentary views in side 60 elevation of a last in its bottom up position as required in use in shoe factories, Fig. 2 being broken out at the side for clearly showing the internal construction; and Fig. 3 is a vertical cross section through the hinge pivot 65 of the last.

My last is so simple in its construction that it may be explained in a few words: The forepart 1 and heel-part 2 are joined by a plate hinge 3 secured rigidly in the heel-part by a 70 transverse pin 4 and a heavy rivet or bolt 5, and free to turn in the forepart on a heavy tool-steel pin 6, narrow kerfs 7, 8 being provided respectively in the forepart and heel-part to receive said hinge-plate. The hinge- 75 plate extends upwardly toward the top of the last at 9 throughout the wider portion of the last where the greatest strength is afforded for resisting twisting strains such as are due to the rolling and rocking leveling pressures 80 which proceed lengthwise along the bottom of the shoe in the process of bottom-leveling. The heel-part is severed from the forepart along an irregular line of cut forming a top 85 gap bounded by a curvature 10 on the forepart and 11 on the heel-part, which fit into each other when the last is collapsed, as shown in Fig. 1, and a preferably straight lower portion 12 and approximately horizontal cut 13 connecting the upper portion with 90 said straight lower portion. This severing arrangement provides overlapping shoulders 14, 15, shown separated in Fig. 1 and in mutually supporting contact in Fig. 2. This broad and approximately horizontal ledge is 95 located in a horizontal plane above the pivot pin 6 and between the two securing pins 4, 5, and is at the widest part or bulge of the waist, as best shown in Fig. 3. Thus, when the last is subjected to pressure, it is evident, viewing 100 Fig. 2, that the heavy shoulder 15 of the heel-part receives practically all the vertical strain, said strain being transmitted thereto by the correspondingly heavy shoulder 14, both of said shoulders extending entirely 105 across the last at the widest part of the waist as stated. This relieves the pivot pin 6 of most of the strain which has hitherto been brought upon it, so that there is no longer the liability of its pulling the wood of the fore- 110

part out endwise. The direction of the cut 12 also aids somewhat, as it laps over the heel-part slightly.

My invention is subordinate to the Oscar 5 Heath patent, No. 652,616, of June 26, 1900, over which it is an improvement. In that patent the forepart and heel-part are provided with opposite overlapping portions at the hinge eye or pintle of a leaf hinge set flat- 10 wise longitudinally in the last, said construction being provided for relieving the hinge of certain strains, but said construction merely increased the tendency of the last to split, inasmuch as it brought the entire vertical 15 pressure in one and the same horizontal plane coinciding with the transverse saw cuts occupied by the hinge leaves. Thus, in the Heath construction the twisting strains and the vertical strains were both brought to bear along a single weakened horizontal 20 plane. In my construction these strains are distributed throughout all the wood of the waist of the last, and do not center upon any one plane or point, the twisting strain being largely 25 borne by the vertical extension 9 of the hinge-plate and its engaging slot, and to some extent transmitted to the heavy steel pin 6 and its supporting wood, said pin extending transversely through the body of the 30 last adjacent the lower part of the forepart, and the vertical strain being taken by the horizontally extending shoulders 14 and 15, which are not in line with any pivot or hinge as in Heath, but lie in a horizontal plane 35 which does not include any of the transverse pins 4, 5, 6, but, on the contrary, comes at the widest bulge portion of the waist entirely independent of any natural splitting plane, such as is caused by the location of the hinge 40 in the Heath construction. Also, the construction is such that the heel-part swings instantly entirely clear of the forepart for quick shortening with minimum resistance. The main features of the invention reside, 45 however, in distributing the joint end strains throughout different localities in the wood, so that no disastrous strain can possibly come at one point, and especially so that the strains do not come along any natural line of 50 cleavage or splitting of the wood, said distribution of strains being accomplished by locating a wide or deep vertical hinge-plate centrally in the widest part of the wood of the last-waist, providing the front lower corner 55 of said vertically extending plate with a heavy transverse pivot pin, and forming the overlapping shoulders located intermediate the horizontal planes of the various pivot and retaining pins, said shoulders each hav- 60 ing a vertical backing of solid wood which projects forward beyond the vertical plane of the front edge of the respective projection, or in other words, preferably overhangs or underhangs as the case may be, i. e. the 65 shoulder 15 has an overhanging solid body

of wood above it in the heel-part, so that the heel-part thereby possesses maximum strength of solid uncut wood, and the shoulder 14 has an underhanging or rearwardly projecting solid body of wood below it in the forepart, so that the forepart thereby possesses maximum strength of solid uncut wood.

Having described my invention, what I claim as new and desire to secure by Letters Patent, is:

1. A hinged last, having its forepart and heel-part connected by a deep hinge-plate set vertically in the contiguous walls of said last parts, said hinge-plate having a wide vertical engagement within the forepart substantially commensurate with the bulging portion of the forepart having large transverse width, and a heavy pivot pin extending through the lower part of the forepart and the lower forward corner of said hinge-plate, whereby the twisting strains of the heel-part are transmitted by said hinge-plate in a vertical plane to the central portion of the enlarged part of the rear end of the forepart and by said heavy transverse pin in a horizontal plane to the lower rear portion of the forepart, said hinge-plate being rigidly secured in the heel-part by two transverse pins located respectively in the rear upper corner and rear lower corner of the hinge-plate and extending transversely through the heel-part, said heel-part and forepart being severed by lines of cut forming approximately horizontally overlapping shoulders located in a horizontal plane above the lower heel-part pin and said pivot pin and below the upper heel-part pin, and a gap between said heel-part and forepart extending upwardly from the front normally contacting ends of said overlapping shoulders.

2. A hinged last, having its forepart and heel-part connected by a deep hinge-plate set vertically in the contiguous walls of said last parts, said hinge-plate having a wide vertical engagement within the forepart substantially commensurate with the bulging portion of the forepart having large transverse width, and a heavy pivot pin extending through the lower part of the forepart and the lower forward corner of said hinge-plate, whereby the twisting strains of the heel-part are transmitted by said hinge-plate in a vertical plane to the central portion of the enlarged part of the rear end of the forepart and by said heavy transverse pin in a horizontal plane to the lower rear portion of the forepart, said hinge-plate being rigidly secured in the heel-part by two transverse pins located respectively in the rear upper corner and rear lower corner of the hinge-plate and extending transversely through the heel-part, said heel-part and forepart being severed by lines of cut forming between them approximately horizontally overlapping shoulders located in a horizontal plane

above the lower heel-part pin and said pivot pin and below the upper heel-part pin, and a gap between said heel-part and forepart extending upwardly from the front normally 5 contacting ends of said overlapping shoulders, the walls of said gap having a forward divergent curvature from their meeting ends at said front end of said overlapping shoulders, and the line of cut from the rear end of said 10 overlapping shoulders extending obliquely

downwardly and rearwardly to the bottom of the last.

In testimony whereof, I have signed my name to this specification, in the presence of two subscribing witnesses.
